TIMBER TONG

Carl M. Smock, Sweet Home, Oreg.

Application May 13, 1957, Serial No. 658,756

3 Claims. (Cl. 294—111)

This invention relates to grapple mechanism and more particularly to a novel grapple or clamping mechanism for hoisting pieces such as timber pieces and the like whereby the lifting and transporting of the pieces is greatly facilitated.

The grapple or clamping mechanism of this invention is characterized by construction which enables the pieces to be gripped and hoisted by the mechanism, and then stacked or piled adjacent an obstruction without the grapple mechanism encountering the obstruction to be encumbered thereby. Further, the mechanism incorporates construction features whereby pieces are gripped and subsequently released with a minimum amount of ripping or tearing of the pieces, such as ordinarily occurs with conventional grapple mechanism.

Generally it is an object of this invention to provide a grapple or clamping mechanism wherein the clamping or tong members of the mechanism come together and engage a piece of timber or the like in a novel manner so that the top and only one side of the timber is gripped, thereby enabling the piece to be stacked adjacent an obstruction without interfering with the operation of the grapple.

Another general object of this invention is to provide an improved chuck mechanism for the clamping or tong members of the grapple, operable to bite into and hold securely a timber piece, yet so arranged in the organization with the clamping or tong members of the grapple that they are readily released without ripping across and tearing the piece handled.

Briefly, the grapple or clamping mechanism of this invention comprises a pair of mutually pivoted clamping or tong members, pivoted relative to each other so that the chuck means carried by each of the tong members swings into and grips a piece of timber deposited between the members. One of the tong members has a supporting arm adapted to be laid across the top of the piece to be handled when the grapple is lowered into position prior to hoisting the piece. Depending downwardly from this supporting arm is a gripping arm carried by the supporting arm to one side of the timber piece when the supporting arm is properly positioned over the top of the piece. The other of the tong or clamping members pivots inwardly to engage the top of the timber piece when the grapple is hoisted from the ground. Thus the article handled is engaged by chuck elements which are carried by the tong members of the grapple at points located on the top and to one side of the article.

The supporting arm is supplied with a hoist means located outwardly from the pivot connection for the two tong members, and positioned above the top of a piece of timber when the grapple is set to lift the timber. A line trained about this hoist means and connected at its end to the other of the tong members is operable, when tensioned, to lift the grapping device and the lumber piece therewith and at the same time to pivot the two tong or clamping members so as to bring the chuck elements carried by the members together. The hoist means car-

2

ried by the supporting arm is located in the vicinity of a vertical plane passing through the center mass for the timber prior to hoisting it from the ground. In this way, when the timber is raised, canting or rolling over of the piece is prevented. The timber may then be moved to a new position and deposited with the clamping members occupying approximately the same vertical positioning after the timber is deposited as when the timber was first hoisted.

- 10 The chuck mechanism for each of the tong or clamping members which grip into the timber piece prior to lifting the piece each comprise a series of relatively short gripping teeth or prongs arranged in a row and adapted to grip with relatively small penetration the surfaces of the timber piece. The gripping teeth are curved in a novel manner, so that when moved by pivotal movement of the clamping members, they bite into or are released from the surface of a piece of timber without scraping of the teeth across the surface of the lumber so as to scratch and mar the surface. The grapple mechanism is readily kicked off from a piece of timber after transporting of the timber, the teeth of the chuck mechanism moving out of the lumber in a path conforming more or less to the curvature of the teeth.
- 15 Thus, another feature of this invention is the inclusion in the grapple mechanism of gripping mechanism having teeth or prongs curved in a novel way so that the teeth enter and are removed from the article handled in a path substantially coinciding with the curvature of the teeth.
- 20 Yet another object of this invention is to provide a clamping or grapping mechanism wherein the mechanism is hoisted by means of a line trained about a hoist means located over the top of the article handled generally in the vicinity of a vertical plane passing through its center of mass as it rests on the ground, whereby canting and turning of the article after it is raised for transport is prevented.
- 25 A related object is to provide such a grapple mechanism wherein the hoist means is adjustable over the top of the article handled, permitting the grapple mechanism to be employed most advantageously with articles of various sizes.
- 30 Another object is to provide a grapple mechanism constructed and arranged so that it may be readily released from gripping a timber piece when it is desired to remove the mechanism after transport of the piece.
- 35 These and other objects and advantages are attained by the present invention which is described hereinbelow in conjunction with the accompanying drawings wherein:

Fig. 1 is a side view of a grapple mechanism embodying this invention;

Fig. 2 is a top view of the mechanism illustrated in Fig. 1; and

Fig. 3 is another side view of the mechanism in Fig. 1 showing the position of the parts of the mechanism when it is gripping a piece of timber.

Referring to the drawings wherein an embodiment of this invention is illustrated, the grapple mechanism comprises generally a pair of clamping or tong members indicated generally at 11 and 12, pivotally connected one to the other as by pivot pin 13.

With reference to clamping member 11, this member comprises a supporting arm 16 adapted to be positioned over the top surface of a piece of timber, illustrated in the drawings as lumber stick 14, when the grapple is initially lowered thereon, as illustrated in Fig. 1. Affixed to supporting arm 16 and depending downwardly therefrom at an oblique angle is a gripping arm 17. The grapple mechanism of this invention is particularly adapted for handling square timber, such as timber 14. By placing dependent gripping arm 17 at an oblique angle relative to arm 16, the outer arm rides free of the sides

of the timber when member 11 is lowered over the timber, enabling the corner of the timber to move readily with a snug fit into the re-entering corner defined by the juncture of the inner edges of arms 16 and 17. The corner defined by these edges is indicated at 19.

The supporting and gripping arms of clamping member 11 may conveniently be prepared from channel-shaped pieces of iron affixed together as by welding at a joint indicated by the dotted line 18. The upstanding flanges of the channel iron contribute strength to the member, enabling it to take a considerable amount of twisting without deformation. In addition, the flanges carried by the gripping arm portions of member 11 provide a means for mounting a grip rod or handle useful in releasing the grapple as described hereinbelow.

Clamping member 12, which also may be prepared from segments of channel iron suitably affixed together, has a gripping or fastening arm 21 adapted to lie over the top of a piece of timber when the grapple is lowered thereon, and an actuating arm 22 projecting upwardly therefrom and spaced behind gripping or fastening arm 21 when arm 21 is moved toward arm 17 by relative pivotal movement of members 11 and 12.

The width of clamping member 12 is somewhat less than the inner dimension between upstanding flanges 24 and 25 of supporting arm 16 and flanges 29, 30 of arm 17. This enables clamping member 12 to swing freely inside the area bounded by flanges 24, 25, and flanges 29, 30. Cutout portions 26 and 28 are provided in arms 16 and 17 to accommodate pivotal movement of clamping member 12 relative to clamping member 11. Preferably actuating arm 22 of member 12 is somewhat longer than the gripping arm 21, so that while arm 21 can swing freely below supporting arm 16, the end of arm 22 serves as an abutment means inhibiting pivotal movement of member 12 relative to member 11 when the arm 22 comes into contact with a shoulder 27 defined by the edge of cutout portion 26. Fastening arm 21 swings between a retracted position, wherein the outer end of the arm is disposed above the base of supporting arm 16, past an aligned position with the supporting arm, to a penetrating position wherein the outer end of the arm is below the lower base of supporting arm 16.

The gripping arm of each of the clamping members is provided with chuck mechanism spaced outwardly from pivot pin 13. Each of the chuck mechanisms comprises a series of hooked prongs or teeth, indicated for arms 17 and 21 at 31 and 32, respectively. These are removable to accommodate replacement should the teeth become worn. In the embodiment illustrated, each prong includes at one of its ends a stud portion 33 which is inserted through an accommodating bore formed in the gripping arm supporting the tooth. Each prong is affixed to its gripping arm by means of a nut 36 threaded onto the end of the stud portion. A series of relatively short teeth are used, and these are spaced in a row along each gripping arm. It has been found that such an arrangement of the gripping prongs or teeth permits an excellent grip to be obtained with relatively slight penetration of the lumber. The use of prongs which only slightly penetrate the lumber has been found to decrease inadvertent marring or scratching of the lumber.

As stated hereinbefore, each of the teeth are curved in a novel manner which enables the teeth to enter and then be drawn out of the surface which they engage, while moving in a path more or less coinciding with the curvature of the teeth. That is to say, the teeth move into and out of the lumber without appreciable shifting of the teeth laterally of the lumber, such as would cause scratching or tearing of the lumber. To this end, teeth 31 of gripping arm 17 are curved about a radial center substantially coincident with corner 19 defined by the juncture of the inner edges of supporting arms 16 and gripping arm 17. As will be described hereinbelow, pivotal movement of clamping member 11 takes place about

a point more or less corresponding to corner 19. In this way, when teeth 31 are inserted into a side of a piece of lumber, the path of movement of the teeth corresponds to their curvature.

- 5 Teeth 32 of gripping arm 21 are curved about a radial center substantially coincident with pivot pin 13 of the grapple. As will be described hereinbelow, during operation of the device, clamping member 12 tends to pivot inwardly against a piece of timber about this pivot point.
- 10 In this manner, the path of teeth 32 into a piece of lumber conforms substantially with the curvature of the teeth. Pivot pin 13, as illustrated in the drawings, preferably is situated outwardly of corner 19 and slightly upwardly therefrom, so that in penetrating a piece of timber, teeth 32 move for the most part in a more or less vertical plane.

Extending through flanges 29, 30 of gripping arm 17 is a grip rod or handle 46. This handle provides a means for loosening the grapple mechanism after a piece of

- 20 timber has been transported, as will be described.

Adjacent the outer end of supporting arm 16 is a hoist means indicated at 47. Hoist means 47 comprises a pin 50 having expanded ends 48 and 49 and mounted in flanges 24, 25 of gripping arm 16. The grapple of this invention is lifted up by means of a flexible line 51, which may be a cable or rope, trained about hoist pin 50 with its end affixed to the end of actuating arm 22. The flexible line, when tensioned, has the double effect of pulling upwardly on the grapple mechanism, as well as imparting relative pivotal movement between clamping members 11 and 12 of the mechanism.

Pin 50 is adjustable longitudinally along the length of gripping arm 17, enabling the lift point for the grapple to be positioned over the timber to be transported. To this end, slots, such as slot 52, are provided in upturned flanges 24, 25 of supporting arm 16. The upper edge of each of the slots has seats or saddles 54 formed therein, spaced at regular intervals along the top of the slots. When pin 50 is raised upwardly by the action of the cable or line reeved thereabout, the pin sits firmly into the seat selected.

The grapple mechanism of this invention may be employed for lifting a piece of timber without having the timber cant or roll after it is hoisted. The grapple has perhaps its greatest utility with lumber pieces having a rectangular or square cross section. Frequently with timbers such as these, which may range for example from 6 x 10's to 12 x 20's, it is desirable to stack the timbers into a pile with succeeding pieces laid closely adjacent the forming stack. The grapple of this invention enables the operator to grasp a timber piece, transport it, stack it, and then release it without interference from the already formed stack.

Referring to the drawings, in operation, the grapple is first lowered over a piece of timber until load supporting arm 16 of clamping member 11 rests over the top side of the timber. Corner 19 is fitted on the corner of the timber. Gripping arm 17, which depends at an obtuse angle downwardly from the supporting arm, lies to one side of the timber with teeth 31 carried by the arm out of engagement with the timber piece. This condition of the parts is illustrated in Fig. 1.

Upon tensioning of line or cable 51 reeved about pin 50, clamping member 11 first pivots about corner 19 with curved teeth 31 carried by the gripping arm for the member penetrating into the sides of the timber. Penetration of the teeth continues until the resistance encountered by the teeth creates a reaction force in line 51 urging actuating arm 22 of clamping member 12 to rotate in a clockwise direction in Figs. 1 and 2 about pin 13. Pivotal movement of member 12 causes teeth 32 carried by the member to penetrate the upper surface of the timber piece. Movement of the teeth 31 and 32 into the timber continues until the teeth become fully lodged. Further tensioning of line 51 operates to lift the grapple

and the timber grasped thereby enabling the timber to be transported. Pin 50, prior to fastening the grapple, is positioned over the piece of timber so as to lie near a vertical plane passing up through the center of gravity of the timber piece as it lies on the ground. In this manner the timber will not roll or cant when picked up by the grapple. By maintaining the vertical positioning of the timber piece, the timber may be laid against a stack of other timbers, without having parts of the grapple mechanism become encumbered with the already formed stack.

When it is desired to release the grapple mechanism from a piece of timber, the operator need only kick down on supporting arm 16, thereby pivoting clamping member 11 about corner 19 so that teeth 31 are removed from the timber. Teeth 32 of gripping arm 21 may then be loosened by pulling up on rod 46, thereby slightly to wedge apart the wood around the teeth, subsequently relaxing the rod and then lifting the whole assembly.

In summary, it will be noted from the above that when the timber piece is finally placed after transport, it may be laid directly adjacent other timbers without the necessity of strong-arming the piece over after removing the grapple mechanism. Further, the grapple mechanism is uniquely capable of release from timbers without the teeth of the mechanism scraping across the surfaces of the timbers. The penetration of teeth 31, 32 is maintained at a minimum by employing a plurality of relatively short teeth curved in the novel manner described.

If the grapple is to be used with a wide variety of lumber sizes, although a stationary mount for pin 50 may be adequate, it is preferable that an adjustable mount such as the one illustrated be used, since this permits positioning of the hoist pin more closely adjacent a vertical plane passing through the center of mass for the lumber.

As used herein, the phrase "unrestricted re-entering corner" refers to a re-entering corner which is free of any member or part subtending the corner thereby to close it off.

It is claimed and desired to secure by Letters Patent:

1. A grappling device for timber pieces comprising a rigid first tong member of substantially L-shaped configuration having an elongated, horizontal supporting arm and an elongated gripping arm joined at one of the latter's ends to one end of said supporting arm; said gripping arm depending downwardly from said supporting arm and defining with said supporting arm a substantially right-angled, unrestricted re-entering corner adapted to be seated on the edge of a timber piece; a second tong member having an elongated, substantially horizontal fastening arm extending in the direction of said supporting arm with one end of the fastening arm adjacent said one end of said supporting arm and the other end of the fastening arm spaced from said one end of said supporting arm in the direction of the other end of said supporting arm; said second tong member also having an elongated actuating arm rigidly joined at one of the latter's ends to said one end of said fastening arm and projecting upwardly at an angle from said fastening arm; pivot means pivotally connecting said one end of said fastening arm to said one end of said supporting arm for pivotal movement of said other end of said fastening arm about said pivot means toward and away from said other end of said gripping arm; said other end of said fastening arm pivoting between a position spaced above, and a position spaced below the base of said supporting arm and within said re-entering corner; said other end of said actuating arm being disposed above said pivot means throughout movement of said other end of said fastening arm between the two aforementioned positions; said other end of said fastening arm and said other end of said gripping arm pivoting about said pivot means in substantially a common plane; hoist means carried by said supporting arm adjacent said other end

of said supporting arm; flexible line means secured to said other end of said actuating arm and trained about said hoist means operable when tensioned to pivot said tong members in opposite directions; and gripping means secured to said other ends of said fastening and gripping arms with the gripping means of the two arms projecting toward each other.

2. A grappling device for timber pieces comprising a rigid first tong member of substantially L-shaped configuration; said first tong member having an elongated, horizontal supporting arm and an elongated gripping arm joined at one of the latter's ends to one end of said supporting arm; said gripping arm depending downwardly from said supporting arm and defining with said supporting arm a substantially right-angled, unrestricted re-entering corner adapted to be seated on the edge of a timber piece; a second tong member having an elongated, substantially horizontal fastening arm extending in the direction of said supporting arm with one end of the fastening arm adjacent said one end of said supporting arm and the other end of the fastening arm spaced from said one end of said supporting arm in the direction of the other end of said supporting arm; said second tong member also having an elongated actuating arm rigidly joined at one of the latter's ends to said one end of said fastening arm and extending upwardly at an angle from said fastening arm; pivot means pivotally connecting said one end of said fastening arm to said one end of said supporting arm for pivotal movement of said other end of said fastening arm about said pivot means toward and away from said other end of said gripping arm; said other end of said fastening arm pivoting between a position spaced above, and a position spaced below the base of said supporting arm and within said re-entering corner; said other end of said actuating arm being disposed above said pivot means throughout movement of said other end of said fastening arm between the two aforementioned positions; said other ends of said fastening arm and said gripping arm pivoting about said pivot means in substantially a common plane; hoist means; means mounting said hoist means on said supporting arm adjacent said other end of said supporting arm accommodating positioning of the hoist means longitudinally of said supporting arm whereby the hoist means may be placed over the center of gravity of a timber piece handled by the device; flexible line means secured to said other end of said actuating arm and trained about said hoist means operable when tensioned to pivot said tong members in opposite directions; and gripping means secured to said other ends of said gripping and fastening arms with the gripping means of the two arms projecting towards each other.

3. A grappling device for timber pieces comprising a rigid first tong member of substantially L-shaped configuration; said first tong member having an elongated, horizontal supporting arm and an elongated gripping arm joined at one of the latter's ends to one end of said supporting arm; said gripping arm depending downwardly from said supporting arm and defining with said supporting arm an obtuse but substantially right-angled, unrestricted re-entering corner adapted to be seated on the edge of a timber piece; a second tong member having an elongated, substantially horizontal fastening arm extending in the direction of said supporting arm with one end of the fastening arm adjacent said one end of said supporting arm and the other end of the fastening arm spaced from said one end of said supporting arm in the direction of the other end of said supporting arm; said second tong member also having an elongated actuating arm rigidly joined at one of the latter's ends to said one end of said fastening arm and extending upwardly at an angle from said fastening arm; pivot means pivotally connecting said one end of said fastening arm to said one end of said supporting arm for pivotal movement of said other end of said fastening arm about said pivot means to

ward and away from said other end of said gripping arm; said other end of said fastening arm pivoting between a position spaced above, and a position spaced below the base of said supporting arm and within said re-entering corner; said other end of said actuating arm being disposed above said pivot means throughout movement of said other end of said fastening arm between the two aforementioned positions; said other ends of said fastening arm and said gripping arm pivoting about said pivot means in substantially a common plane; a first series of relatively short teeth mounted on said other end of said fastening arm; and a second series of relatively short teeth mounted on said other end of said gripping arm; the teeth of one series projecting toward the teeth of the other series and being shaped to bite into a timber piece with slight penetration; the teeth of said second series

5 curving about a radial center substantially coinciding with the apex of said re-entering corner; the teeth of said first series curving about a radial center substantially coinciding with the pivot axis of said pivot means; hoist means carried by said supporting arm adjacent said other end of said supporting arm; and flexible line means secured to said other end of said actuating arm and trained about said hoist means operable when tensioned to pivot said tong members in opposite directions with the first and second series of teeth swinging toward each other.
